UNITED STATES PATENT OFFICE

ARTHUR E. KRICK, OF DANVILLE, INDIANA, ASSIGNOR TO THE NATIONAL DRY KILN COMPANY, OF INDIANAPOLIS, INDIANA, A CORPORATION OF INDIANA

AUTOMATIC LIFT

Application filed September 28, 1927. Serial No. 222,448.

It is the object of my invention to provide an automatic control device for maintaining at a constant level the top of a pile, as of lumber, from which boards or sheets are being removed, so that as such boards or sheets are removed the pile will be raised to keep its top substantially at a given level. In this way, as the boards or sheets are taken from the pile, for instance to a planer or other machine, the raising of the pile maintains the top of the pile always at a convenient level for the operator to feed the machine.

It is a further object of my invention to provide such an automatic control device which can be thrown into and out of operative condition as desired; and which can be moved to various positions and adjusted to various controlling levels as desired.

It is a still further object to provide a hand control device and a safety device which are associated with the automatic control device in a new way, to get certain interlocking controls between them.

I have illustrated my invention diagrammatically, to simplify the understanding thereof. The various devices conveniently illustrated may take any suitable form, and may be varied in a number of ways; so that the drawing is illustrative merely.

The single figure of the drawing is a diagram illustrating my invention.

The platform 10 of a lumber-lift is shown as being raisable and lowerable by an electric motor 11, connected to the supporting stem 12 of the platform through any suitable gearing, including a rack and pinion in the illustrative form shown. The motor 11 is a reversible motor, so that it raises or lowers the platform 10 according to the direction in which the motor rotates. The platform 10 is shown as being raisable and lowerable with relation to a floor 13; and as being movable to levels both above and below such floor. Conveniently the platform 10 is provided with tracks 14 for carrying a truck 15 of any usual type; which tracks 14 may be brought to the level of the floor 13, or of tracks on said floor if such tracks are provided, to per-

mit the truck 15 to be rolled on to and off of the platform 12.

The motor 11 is shown as a three-phase alternating current motor, supplied from a supply line 20 through a three-pole double-throw reversing switch 21; which switch in middle position disconnects the motor 11, but in its two extreme positions connects the motor 11 to the supply line 20 for opposite directions of rotation. The switching means is shown as a single double-throw switch, because that is perhaps the simplest way to obtain the desired action of preventing the closing of the circuit for both directions of rotation of the motor 11 at once. However, this illustration is not intended to limit the switch to a single double-throw switch, as obvious variations are readily apparent.

The switch 21 has two operating solenoids 23 and 24, for moving it to its opposite extreme positions when such solenoids are energized. The solenoids 23 and 24 are for producing upward and downward movement respectively of the platform 10. The switch 21 also has centering springs 25 which tend to move it to and hold it in its middle or open position, and do so when the solenoids 23 and 24 are both inactive.

There are upper and lower limit switches 27 and 28, provided in the circuits of the upward solenoid 23 and downward solenoid 24 respectively for insuring the de-energization of those solenoids when the platform 10 reaches its upper and lower safe limits of movement respectively. There are one or more sets of control push-buttons, only two sets being shown for simplicity. Each of these sets comprises three push-buttons 29, 30, and 31, for normally producing upward movement, downward movement, and stopping respectively. The "up" and "down" push-buttons 29 and 30 are electrically interlocked, by having not only their front contacts for producing up and down movement respectively, but by also having back contacts of which those of one push button (of all sets) must be connected by these push-buttons in order for the circuit controlled by the front contacts of the other of said push-buttons to be completed. That is, in

55

100

order to close the "up" circuit through the solenoid 23 it is not only necessary that the "up" push-button 29 of a push-button set be depressed but that the "down" push-buttons 30 of all sets be not depressed; and in order to close the "down" circuit through the solenoid 24 it is not only necessary that the "down" push-button 30 of a push-button set be depressed but that the "up" push-buttons 29 of all sets be not depressed. The "stop" push-button 31 has back contacts only; and the connections are such that these "stop" push-buttons of all sets must be un-depressed in order for either the "up" circuit or the "down" circuit to be closed or to remain closed; so that by the depressing of any "stop" push-button 31 the circuit of either solenoid 23 or 24 which may be completed is opened, and the motor 11 stopped.

20 Thus the motor 11 may be stopped at any time by depressing any "stop" push-button 31; it may be caused to move upward by depressing any "up" push-button 29, but only if both the "down" push-buttons 30 and the "stop" push-buttons 31 of all sets are not depressed; it may be caused to move downward by depressing any "down" push-button 30, but only if both the "up" push-buttons 29 and the "stop" push-buttons 31 of all sets are not depressed.

In addition, the main switch 21 has a supplemental or holding switch 32, which is swung into contact with the switch contacts 33 and 34 respectively upon the energization 35 of the solenoids 23 and 24 respectively. When either solenoid 23 and 24 is initially energized by the depression of an "up" or "down" push-button 29 or 30 respectively, the holding switch 32 normally closes a circuit in shunt to said respective push-buttons, through the contact 33 or 34 respectively, for maintaining the energization of the solenoid 23 or 24 after the associated push-button has been released; so that only a momentary depression of the proper push-button is necessary to produce upward or downward movement of the platform. Such upward or downward movement continues until a "stop" push-button 31 is depressed, or until the proper limit switch 27 or 28 is opened.

50 (As so far described, the mechanism is not new; but the automatic control now to be described, and the combination thereof with the other mechanism, are new so far as I know.)

The holding switch 32 may always be effective for the "down" solenoid 24, until the limit switch 28 is opened or the "stop" push-button 31 or "up" push button 29 is depressed; but for the "up" solenoid 23 the holding switch 32 may be effective to maintain the circuit until the "stop" push-button 31 or the "down" bush-button 30 is depressed, or the limit switch 27 is opened only if and when the automatic control device is

not in operative position, and is ineffective when the automatic control device is in operation.

The automatic control device, in its preferred form, is on a movable stand 40 which has a vertical post and which may be moved to any convenient position so that it will not interfere with but will be sufficiently close to the lumber 41 on the platform 10. Vertically adjustable on the post of this stand is a block 42, on which is pivoted a swinging arm 43 which may be swung downward to the full-line position or up and back to the dotted-line position, for making the automatic control device operative and inoperative respectively.

70 The swinging arm 43 carries two switches 44 and 45, which are spring-pressed to open position and to closed position respectively.

75 The switch 44 is shown as a simple leaf spring switch; which tends to spring open and does so when the arm is raised to the dotted line position, but which is pressed to closed position against its co-operating contact 46 when the arm 43 is swung downward to its working position. For this, the block 42 carries a stop screw 47 for limiting the downward swing of the arm 43, and a second switch-closing screw 48 which engages the switch 44 and forces it against the 80 contact 46 when the arm 43 is swung downward.

85 The switch 45 is shown as having a closing spring 49 which tends to press it against the two associated contacts 50 and 51. The switch arm 45 has a projection which carries a roller 52, which the spring 49 tends to press away from the swinging arm 43 to close the switch 45, but which when moved toward the arm 43 opens such switch by 90 separating the arm 45 from the contacts 50 and 51. When the arm 43 is swung downward, the roller 52 is placed over the pile of lumber 41; and the roller is moved upward to open the associated switch 45 when the top course of lumber is raised to the desired level, and drops to close such associated switch 45 when the top course of lumber is removed. With the arm 43 in its full-line or operative position, this movement of the roller 52 and switch 45 causes the motor 11 to start to raise the platform 10 when the top course of lumber is removed, and to continue raising it until the next lower course of lumber (now become the top 105 course) has risen sufficiently to raise the roller 52 and open such switch 45.

110 The switch 45 is connected in series in the holding circuit for the "up" solenoid 23, so that it must be closed in order that the holding circuit may be completed; and the switch 44 is connected directly across the holding switch for such "up" solenoid, or between the holding-switch arm 32 and the contact 33, so that unless the switch 44 is 115

open the opening and closing of the holding switch on the contact produces no effect.

In consequence, when the switch-arm 43 is raised to its dotted line or inoperative position, the switch 45 is closed and the switch 44 opened; so that the motor 11 and platform 10 are controlled wholly by the push buttons 29, 30, and 31, with the regular holding circuits controlled by the holding switch 32, just as though the automatic control device were not present. On the other hand, when the swinging arm 43 is swung down to its horizontal or operative position, several things occur:

1. The effect of the "down" push-button 30 and of the "stop" push-button 31 are not affected, but remain as they were before. They can take contact at any time, regardless of the automatic control; although for a "down" push-button to take control it is necessary that all "up" push-buttons be un-depressed.

2. The limit switches 27 and 28 remain effective as before.

3. The "up" push-buttons 27 become effective only to produce upward movement of the platform 10 above the level set by the automatic control device and only so long as the push-button 29 is held depressed, (within the limit permitted by the "up" limit switch 27), but becomes ineffective to initiate upward movement which continues after the "up" push button is allowed to rise, and becomes ineffective to control the platform rise while the platform is below the level set by the automatic control device since at that time the platform is moving upward under automatic control.

4. The holding switch 32 remains effective to control the holding circuit for the "down" solenoid 24; but becomes ineffective to control the holding circuit for the "up" solenoid 23.

Thus the swinging of the automatic-control arm 43 from operative to inoperative position, or vice versa, modifies the action of the manual control, and makes the control of the upward movement of the platform 10 primarily dependent upon the level of its top course of lumber.

This will be readily apparent from tracing the circuits; which tracing has been deferred until after the description of the general operation.

5. The control circuits are shown connected between the middle and left-hand leads of the main circuit 20.

Starting at the middle lead, the current for downward operation passes by the wire 60 to the solenoid 24, thence by the wire 61 to one contact of the "down" limit switch 28; thence by the wire 62 to one of the back contacts of one "up" push-button 29; thence in series through the back contacts of all the "up" push-buttons, and from the final back con-

tact of the "up" push-buttons by the wire 63 to one of the front contacts of each "down" push-button 30. If now any such "down" push-button is depressed, the current thence continues from the other front contact of said "down" push-button 30 to the wire 64, and by it to one of the back contacts of one "stop" push-button 31; then in series through all the back contacts of the "stop" push-buttons, and from the final back contact of the "stop" push-buttons 31 by the wire 65 to the left-hand lead of the circuit 20. Thus, if all "up" push-buttons and all "stop" push-buttons 31 are un-depressed, the depressing of any "down" push-button 30 closes the circuit for the "down" solenoid 24, which acts to swing the main switch 21 and the holding switch 22 to the right into contact with their respective buttons. This closes the circuit for the motor 11, in the proper direction to cause it to lower the platform 10. The swinging of the switch arm 32 to the right closes a circuit in shunt to the front contacts of the "down" push-buttons 30; so that the depressed "down" push-button need not be held, as if it is released the circuit closed by it is still maintained through the switch 32 in contact with the button 34. This circuit is by way of the wire 66 which leads from the wire 63 to the contact 34; and by a wire 67 which leads from the wire 64 to the switch arm 32. When the "down" circuit for the motor 11 is thus closed, such motor continues in operation to cause lowering of the platform 10 until the circuit of the down solenoid 24 is opened either by the depression of an "up" push-button 29, the depression of a "stop" push-button 31, or the automatic opening of the "down" limit switch 28. This control of the down movement is entirely independent of and unaffected by the position of the swinging arm 43.

Again starting at the middle lead of the main circuit 20, the current for upward operation passes by the wire 70 to the solenoid 23, thence by the wire 71 to one contact of the "up" limit switch 27; thence by the wire 72 to one of the back contacts of one "down" push-button 30; thence in series through the back contacts of all the "down" push-buttons, and from the final back contact of the "down" push-buttons by the wire 73 to one of the front contacts of each "up" push-button 29. If now any such "up" push-button is depressed, the current thence continues from the other front contact of said "up" push-button 29 to the wire 74, and by it to the wire 64 and to one of the back contacts of one "stop" push-button 31; then in series through all the back contacts of the "stop" push-buttons, and from the final back contact of the "stop" push-buttons 31 by the wire 65 as before to the left-hand lead of the circuit 20. Thus, if all "down" push-buttons and all "stop" push-buttons 31 are un-de-

pressed, the depressing of any "up" push-button 29 closes the circuit for the "up" solenoid 23, which acts to swing the main switch 21 and the holding switch 22 to the left into contact with their respective buttons. This closes the circuit for the motor 11, in the proper direction to cause it to raise the platform 10. The swinging of the switch arm 32 to the left closes a circuit in shunt to the 5 front contacts of the "up" push-buttons 29, provided the swinging arm 43 is in its upper or inoperative position; so that under those circumstances the depressed "up" push-button need not be held, as if it is released the 10 circuit closed by it is still maintained through the switch 32 in contact with the button 33. This circuit is by way of the wire 75 which leads from the wire 73 to the contact 50, thence by the switch arm 45 to the 15 contact 51, thence by the wire 76 to the contact 33; and by the wire 67, already referred to, which leads from the wire 74 (as well as from the wire 64) to the switch arm 32. When the "up" circuit for the motor 11 is 20 thus closed, such motor continues in operation, provided the switch arm 43 is in raised or inoperative position, to cause raising of the platform 10 until the circuit of the "up" solenoid is opened either by the depression 25 of a "down" push-button 30, the depression of a "stop" push-button 31, or the automatic opening of the "up" limit switch 27. This control of the up movement is thus dependent upon the position of the swinging arm 43. 30 In the immediately preceding paragraph, it is assumed that the swinging arm 43 is in its raised or inoperative position. If such swinging arm 43 is swung down to its full-line or operative position, the downward control 35 remains the same as before, under full control by the push buttons and "down" holding circuit, and the "down" push-buttons may supervene and take control fully away from the automatic control device. But the control 40 of the up movement becomes different by the swinging down to operative position of the arm 43. Primarily, such control is made automatic, to cause raising of the platform 10 whenever the top of the pile of lumber 41 is below a certain level, and to stop 45 such raising when the top of the pile of lumber reaches that level. The swinging down of the arm 43 closes the switch 44; and opens the switch 45 if the top of the pile of lumber 50 41 is sufficiently high. If the top course of lumber is removed, the roller 52 drops, to close the switch 45; which closes the circuit for the "up" solenoid 23 through the parts 55 70, 23, 71, 27, 72, back contacts of the "down" push-buttons 30, to which point the circuit is the same as already described; and thence by way of the wire 75, contact 50, switch 45, contact 51, wire 79, switch arm 44, contact 46, wire 80, wire 67, wire 64, back contacts 60 65 of the "stop" push-buttons 71, and wire 65

to the left-hand lead of the main circuit 20. This starts the motor 11 in operation; and such operation continues until the top of the lumber pile strikes the roller 52 and raises it to break the aforesaid circuit at the switch 70 45.

It still remains possible, even under this automatic control, to produce at will downward movement of the platform 10 by depressing a "down" push-button 30; and to 75 take away the automatic control entirely by such depression of such push button. It is also still possible, as before, to stop the upward operation by depressing a "stop" push button 31, but such stopping only continues 80 while the "stop" push-button is depressed if the top of the lumber pile is below the desired level, instead of continuing indefinitely as it does if the arm 43 is in its up or inoperative position. Either of those operations 85 breaks the control circuit just above described.

The downward movement produced by the depressing of a "down" push-button 30, when once initiated even with the swinging arm 43 90 downward, continues after the release of the depressed "down" push button, because of the completion of the holding circuit by the wires 66 and 67 and the holding switch 32 in contact with the switch button 34, until 95 stopped by depressing a "stop" push-button or an "up" push-button or the opening of the "down" limit switch. When such downward movement is stopped, however, if the top of the pile of lumber 41 is lower than the 100 predetermined level and the arm 43 is still down, the platform is immediately started upward under the control of the roller 52 and the switch 45.

The automatically controlled upward 105 movement produced by having the swinging arm 43 in its operating position may be supplemented by the "up" push-button 29. By depressing such "up" push-button 29, the platform 10 may be made to travel upward 110 independently of the roller 52 and switch 45 and at a point higher than the automatic control would stop the upward movement; but to do this it is necessary to hold the push button 29 down for the full extent of this desired additional upward movement, because the holding circuit for the up movement is then broken at the switch 45. This additional upward movement of the lumber pile may be obtained without breakage, because the additional rise of the lumber pile, after it opens the switch 45 merely serves to tilt the arm 43 115 upward about its pivot.

I claim as my invention:—

1. In combination, an elevator platform 125 for supporting a pile of layer material, and a movable automatic-control device which may be moved into or out of operative position to co-operate with the top of said pile to control automatically the rising of the elevator, 130

- 5 said movable automatic-control device being provided with mechanism for making the automatic control operative and inoperative respectively by the movement of said control device into and out of operative position.
- 10 2. In combination, an elevator platform for supporting a pile of layer material, a standard movable to various positions around said elevator platform, a block vertically adjustable along said standard, a control arm mounted on said block and movable to operative and inoperative positions in the former of which it may co-operate with the top of the pile on said elevator platform, a control device on said arm for co-operating with the top of said pile when the arm is in operative position to control the rise of the elevator to maintain the top of said pile at a constant level as material is removed from said top, and a second control device on said arm for making the first control device operative to produce such automatic control only when the arm is in operative position.
- 15 3. In combination, an elevator platform for supporting a pile of layer material, a standard movable to various positions around said elevator platform, a control arm mounted on said standard and movable to operative and inoperative positions in the former of which it may co-operate with the top of the pile on said elevator platform, a control device on said arm for cooperating with the top of said pile when the arm is in operative position to control the rise of the elevator to maintain the top of said pile at a constant level as material is removed from said top, and a second control device on said arm for
- 20 making the first control device operative to produce such automatic control only when the arm is in operative position.
- 25 4. In combination, an elevator platform for supporting a pile of layer material, a standard movable to various positions around said elevator platform, a control arm mounted on said standard and movable to operative and inoperative positions in the former of which it may co-operate with the top of the pile on said elevator platform, a control device on said arm for cooperating with the top of said pile when the arm is in operative position to control the rise of the elevator to maintain the top of said pile at a constant level as material is removed from said top, and a second control device on said arm for
- 30 making the first control device operative to produce such automatic control only when the arm is in operative position.
- 35 5. In combination, an elevator platform for supporting a pile of layer material, a control station by which upward and downward movements and stopping of said elevator platform may be obtained at will, and an automatic control device which may be moved into and out of operative position in co-operation with a pile on said elevator platform to automatically control the rising of said platform to maintain a predetermined level of the top of said pile as material is removed from said top, and means interconnecting said automatic control device and said control station for modifying the effect producible by said control station according as the automatic control device is moved into or out of operative position.
- 40 6. In combination, an elevator platform for supporting a pile of layer material, a control arm movable to operative and inoperative positions in the former of which it may co-operate with the top of the pile on said elevator platform, a control device on said arm for co-operating with the top of said pile when the arm is in operative position to control the rise of the elevator to maintain the top of said pile at a constant level as material is removed from said top, and a second control device on said arm for making the first control device operative to produce such automatic control only when the arm is in operative position.
- 45 7. In combination, an elevator platform for supporting a pile of layer material, an electric motor for raising and lowering said elevator platform, a manual control device for controlling said electric motor to produce both the rise and the descent of said elevator platform, and an automatic control device responsive to the level of the top of the pile on said elevator platform for controlling said electric motor to produce only the rise of said elevator platform.
- 50 8. In combination, an elevator platform for supporting a pile of layer material, a manual control device for controlling both the rise and the descent of said elevator platform, an automatic control device responsive to the level of the top of the pile on said elevator platform for controlling only the rise of said elevator platform, said automatic control device having both an operative position and an inoperative position, and interconnections between the automatic and manual control devices so that the control produced by the manual control device is altered by the position of the automatic control device.
- 55 9. In combination, an elevator platform for supporting a pile of layer material, a manual control device for controlling both the rise and the descent of said elevator platform, and an automatic control device responsive to the level of the top of the pile on said elevator platform for controlling only the rise of said elevator platform, said automatic control device having both an operative position and an inoperative position, and the automatic and manual control devices being interconnected so that the control produced by the manual control device on the rise only of the elevator platform is modified by the position of the automatic control device.
- 60 10. In combination, an elevator platform for supporting a pile of layer material, a

13 manual control device for starting the elevator platform either upward or downward and for stopping it, an automatic control device responsive to the level of the top of the pile on the elevator platform for controlling only the rise of the elevator platform, and interconnections between said manual and automatic control devices so that the manual control devices may at all times produce 10 stopping of the elevator platform regardless of the automatic control device.

11. In combination, an elevator platform for supporting a pile of layer material, a manual control device for starting the elevator platform either upward or downward and for stopping it, an automatic control device responsive to the level of the top of the pile on the elevator platform for controlling only the rise of the elevator platform, and 16 interconnections between said manual and automatic control devices so that the manual control devices may at all times start descent of the elevator platform regardless of the automatic control device.

12. In combination, an elevator platform for supporting a pile of layer material, a manual control device for starting the elevator platform either upward or downward and for stopping it, an automatic control device responsive to the level of the top of the pile on the elevator platform for controlling only the rise of the elevator platform, and 22 interconnections between said manual and automatic control devices so that the manual control devices may at all times produce either stopping or descent of the elevator platform regardless of the automatic control device.

13. In combination, an elevator platform for supporting a pile of layer material, a manual control device for starting the elevator platform either upward or downward and for stopping it, an automatic control device responsive to the level of the top of the pile on the elevator platform for controlling only the rise of the elevator platform, said 28 automatic control device having both an operative position and an inoperative position, and interconnections between said two control devices so that the control produced by the manual control device is altered by changing the position of the automatic control device.

14. In combination, an elevator platform for supporting a pile of layer material, a manual control device for starting the elevator platform either upward or downward and for stopping it, an automatic control device responsive to the level of the top of the pile on the elevator platform for controlling only the rise of the elevator platform, said 34 automatic control device having both an operative position and an inoperative position, and interconnections between said two control devices so that the control produced by

the manual control device on the rise only of the elevator platform is altered by changing the position of the automatic control device.

15. In combination, an elevator platform for supporting a pile of layer material, a plurality of interconnected manual control devices by each of which the elevator platform may be selectively started upward or downward or stopped, and an automatic control device responsive to the level of the top of the pile on the elevator platform for controlling the rise only of the elevator platform. 70

16. In combination, an elevator platform for supporting a pile of layer material, a plurality of interconnected manual control devices by each of which the elevator platform may be started upward or downward or stopped, an automatic control device responsive to the level of the top of the pile on the elevator platform for controlling the rise only of the elevator platform, said automatic control device having operating and inoperative positions, and interconnections from said automatic control device to said manual control devices so that the effect produced by 80 each of the latter is altered by changing the position of the automatic control device.

17. In combination, an elevator platform for supporting a pile of layer material, operating means for raising and lowering said elevator platform, and an electrical controlling system for said operating means; said electrical controlling system including a manual control device for controlling both the rise and the descent of said elevator platform, 95 and an automatic control device responsive to the level of the top of the pile on said elevator platform for controlling only the rise of said elevator platform. 100

18. In combination, an elevator platform for supporting a pile of layer material, operating means for raising and lowering said elevator platform, and an electrical controlling system for said operating means; said electrical controlling system including a switch which is responsive to the level of the top of the pile on said elevator platform for controlling the rise of the elevator platform, and manual switching mechanism for controlling both the rise and the fall of the elevator platform. 110 115

19. In combination, an elevator platform for supporting a pile of layer material, operating means for raising and lowering said elevator platform, and an electrical controlling system for said operating means; said electrical controlling system including a switch which is responsive to the level of the top of the pile on said elevator platform for controlling the rise of the elevator platform, manual switching mechanism for controlling both the rise and the fall of the elevator platform, said first-named switch being mounted on an arm which is movable to operative and inoperative position, and a switch which is operated 120 125 130

by movements of said arm and which by its position as produced by such movements of the arm controls the effects producible by said manual switching mechanism.

5 In witness whereof, I have hereunto set my hand at Indianapolis, Indiana, this 26th day of September, A. D. one thousand nine hundred and twenty-seven.

ARTHUR E. KRICK.
